UNITED STATES PATENT OFFICE.

CHARLES G. CURTIS, OF NEW YORK, N. Y., ASSIGNOR, BY MESNE ASSIGNMENTS, TO GENERAL ELECTRIC COMPANY, A CORPORATION OF NEW YORK

ELASTIC-FLUID TURBINE.

No. 821,706.

Specification of Letters Patent.

Patented May 29, 1906.

Application filed May 14, 1903. Serial No. 157,067.

To all whom it may concern:

Be it known that I, CHARLES G. CURTIS, a citizen of the United States, residing in the borough of Manhattan, city of New York, 5 State of New York, have invented a certain new and useful Improvement in Elastic-Fluid Turbines, of which the following is a description.

The object I have in view is to secure the 10 adjustment of the stationary and movable elements which form the passage-way for the elastic fluid in the turbine with relation to each other so as to adjust the clearances between these parts and maintain the minimum 15 effective clearance, and particularly to enable this to be done while the turbine is running.

In carrying out my invention the "intermediates"—i. e., the stationary vanes which 20 convey the elastic fluid from one set of moving vanes to another—are carried by a covering-plate mounted to slide in ways upon the shell and adapted to have the necessary amount of movement on such ways without 25 uncovering the opening in the shell. This covering-plate is clamped to the shell by any suitable device, such as bolts passing through slots in the plate, and is adjustable by a screw or screws when such clamping-bolts are 30 loosened. The nozzle is also made adjustable with respect to the moving vanes, and this may be accomplished by adjusting the entire shell upon the shaft by mounting the shell so as to slide in ways upon the base. 35 The shell is clamped to the base by suitable devices, such as bolts passing through slots, and is adjusted longitudinally by a screw or screws when the clamping-bolts are loosened. The wheel carrying the moving vanes is held 40 against longitudinal movement by means of collars on the shaft. The movement of the shell with respect to the wheel adjusts both the nozzle and the intermediates with respect to the moving vanes, while the movement of 45 the covering-plate carrying the intermediates upon the shell enables the adjustment of the intermediates independently of the nozzle and with respect to the moving vanes. It is evident that either or both of these adjustments can be employed.

In the accompanying drawings, Figure 1 is a top view of the turbine with parts broken away. Fig. 2 is a side elevation and partial

section of the turbine. Fig. 3 is an end elevation of the turbine with parts broken away, 55 and Fig. 4 is a perspective view showing the keeper-plate and screw for adjusting the intermediates detached from the turbine and separated from each other.

The base of the turbine has end pedestals 60 1 for supporting the shaft-bearings 2. The end pedestals 1 are connected with side pedestals 3 for supporting the shell. The shell 4 is made in halves divided horizontally at the shaft and provided with stuffing-boxes 5, 65 through which the shaft passes. The two halves of the shell are bolted together by flanges 6, which are in turn bolted to plates 7, resting upon guideways 8 on the side pedestals 3. The plates 7 are clamped to the ways 70 8 by bolts 9, passing through slots in the plates, so as to permit of a limited movement of the plates upon the ways. The side pedestals 3 are connected at one end by a cross-bar 10, in which is mounted the adjusting- 75 screw 11. The inner end of this screw is threaded and engages with the threaded opening in a block 12, secured to the lower half of the shell 4. By turning the screw 11 the shell 4 can be moved a limited distance 80 toward and away from the cross-bar 10. This can only be done when the clamping-bolts 9 are loosened. After the desired movement is secured the bolts 9 are tightened, clamping 85 the shell to the base in the position to which it is adjusted. The shaft 13 is carried by the bearings 2, having collars 14 on opposite sides of these bearings to hold it against longitudinal movement. The shaft passes through the stuffing-boxes 5 and carries within the shell 90 the wheel 15, upon which are mounted the rows of movable vanes 16. The stationary intermediate vanes 17 are carried by a block 18, which is attached to and depends from the covering-plate 19. This covering-plate 95 closes an opening 20 in the top of the shell, through which the intermediates may be removed. The plate is clamped upon the shell by clamping-bolts 21, passing through elongated holes or slots in the plate, so as to permit of the movement of the plate upon the shell to a limited extent lengthwise of the fluid passage-way. The plate 19 is guided in 100 this movement by guideways formed by flanges 22 on the sides of the upper portion 105 of the shell. To secure the movement of the

plate 19 upon the shell, there is provided a screw 23, which is held by a keeper-plate 24, attached to the exhaust-hood 25. The screw 23 engages a screw-threaded opening in the 5 end of the covering-plate 19. When the clamping-bolts 21 are loosened, this covering-plate can be moved on the shell a limited distance without uncovering the opening 20 by turning the screw 23. The nozzle 26 is attached to the shell.

It is evident that by turning the screw 11 the entire shell can be adjusted with reference to the wheel, thus adjusting the nozzle and intermediates simultaneously with reference 15 to the moving vanes carried by the wheel. By turning the screw 23 the intermediates can be adjusted with reference to the moving vanes carried by the wheel. Both these adjustments can be effected while 20 the turbine is running.

What I claim is—

1. In an elastic-fluid turbine, the combination with the casing and the wheel therein carrying two or more rows of moving vanes, 25 of one or more sets of intermediate vanes carried by a support which is adjustable lengthwise of the fluid passage-way so as to adjust the clearances between the moving and stationary vanes, substantially as set forth.
2. In an elastic-fluid turbine, the combination with the casing, the wheel therein carrying moving vanes, the stationary intermediate vanes and the nozzle, of means for adjusting the nozzle and stationary intermediate vanes simultaneously with relation to the moving vanes, and means for adjusting the stationary intermediate vanes with relation to the moving vanes independent of the adjustment of the nozzle, substantially as set 30 forth.
3. In an elastic-fluid turbine, the combination with the casing and the wheel therein carrying moving vanes, of one or more sets of stationary intermediate vanes, means for adjusting said intermediate stationary vanes 35 lengthwise of the fluid passage-way, and means for clamping such vanes in place, both said means being external to the casing, substantially as set forth.
4. In an elastic-fluid turbine, the combination with the casing and the wheel carrying moving vanes, of the intermediates supported by a covering-plate, covering an opening in the casing, means for adjusting the plate 45 over said opening lengthwise of the fluid passage-way, and means for clamping the plate in different positions of adjustment substantially as set forth.
5. In an elastic-fluid turbine, the combination 55 with the casing and the nozzle and sta-

tionary intermediates carried thereby, of the wheel within the casing carrying moving vanes, said wheel being held against displacement lengthwise of the shaft, means for adjusting the position of the casing upon the 65 shaft so as to adjust the clearances between the moving and stationary parts of the turbine, and means for clamping the shell in each position of adjustment, substantially as set forth.

6. In an elastic-fluid turbine, the combination with the casing, the nozzle carried thereby, and the wheel within the casing carrying the moving vanes and held against displacement, of means for moving the casing lengthwise of the wheel-shaft, the stationary intermediate vanes carried by a covering-plate secured to the casing, and means for adjusting the covering-plate upon the casing, substantially as set forth.

7. In an elastic-fluid turbine, the combination with the casing and the nozzle and stationary intermediates carried thereby, of the wheel within the casing carrying moving vanes, the said wheel being held against displacement lengthwise of the shaft, means for adjusting the position of the casing upon the shaft so as to adjust the clearances between the moving and stationary parts of the turbine, and means for adjusting the intermediates in relation to the casing, substantially as set forth.

8. In an elastic-fluid turbine, the combination with the casing and the nozzle and stationary intermediates carried thereby, of the wheel within the casing carrying moving vanes, the said wheel being held against displacement lengthwise of the shaft, means for adjusting the position of the casing upon the shaft so as to adjust the clearances between the moving and stationary parts of the turbine, means for clamping the shell in each position of adjustment and means for adjusting the intermediates in relation to the casing, substantially as set forth.

9. In an elastic-fluid turbine, the combination with the casing and the wheel therein carrying two or more rows of moving vanes, of one or more sets of intermediate vanes, and means for adjusting the intermediate vanes lengthwise of the fluid passage-way so as to adjust the clearances between the moving and stationary vanes, substantially as set forth.

This specification signed and witnessed this 5th day of May, 1903.

CHARLES G. CURTIS.
